REVERSIBLE SPORT SHIRT

Fred Freund, New York, N.Y., assignor to Puritan Sports-wear Corp., Altoona, Pa., a corporation of Pennsylvania

Application October 28, 1959, Serial No. 58,102

Term of patent 14 years

(Cl. D3—25)

I claim:

The ornamental design for a reversible sport shirt, substantially as shown.
